UNITED STATES PATENT OFFICE.

ERNEST C. THORSCHMIDT, OF NEW YORK, N. Y.

STAVE BENDING AND FORMING MACHINE.

1,108,946.

Specification of Letters Patent.

Patented Sept. 1, 1914.

Application filed April 16, 1914. Serial No. 832,285.

To all whom it may concern:

Be it known that I, ERNEST C. THORSCHMIDT, a citizen of the United States, and a resident of New York, borough of Brooklyn, in the county of Kings and State of New York, have invented certain new and useful Improvements in Stave Bending and Forming Machines, of which the following is a specification.

10 This invention relates to stave bending and forming machines particularly of the continuous travel type.

One object of the present invention is to provide a machine of this character which is 15 economical in space and simple and positive in its operation.

Another object is to provide means whereby each stave is accurately bent and formed to the required shape, so as to impart there- 20 to in the same operation, the transverse curvature corresponding to the diameter of the barrel and the longitudinal curvature corresponding to the bilge of the barrel.

A further object is to provide a construction which will permit the free access of the 25 drying current of air to the surfaces of the stave while it is being carried by the conveyor.

A still further object is to provide a machine of comparatively inexpensive construction and which is efficient, durable and reliable in its operation.

The various further objects and advantages will more fully appear from the detailed description and the features of novelty residing in the construction and combination of parts will be particularly pointed out in the claims.

In the drawings illustrating this invention, Figure 1 is an elevation (partly in section along line 1—1 of Fig. 2) of my improved machine, certain parts being broken away for convenience in illustration. Fig. 2 is a plan view with certain parts removed or 45 cut away for the sake of clearness. Fig. 3 is a detail view illustrating the cam for actuating the presser levers. Fig. 4 is an end elevation of the machine partly in section illustrating the feeding mechanism for the 50 staves. Fig. 5 is a detail view illustrating the stops for holding the forms in position.

The present invention is particularly adapted for use in connection with what is known as the "veneer" stave for slack barrel construction. This form of stave is comparatively thin, generally about $\frac{5}{16}$ " in

thickness and is cut flat and to a uniform size. The present invention contemplates the bending and forming of the staves to the required shape while still green, and drying the same until they have obtained their set, all in one continuous operation.

Referring in detail to the drawings, the green staves are fed from a hopper 10, in which the staves are piled just as they come from the veneer machine and cutter in which they are cut flat to a uniform size. The bottom of the hopper is formed with a slot 11, through which the lowermost stave is fed through by a reciprocating feed slide 12. The latter is mounted to reciprocate in guides 13, detachably secured to the standards 14, upon which the hopper together with the guides are supported. The slide 12 is formed at its sides preferably with reduced portions 15, engaging the guides, and an upwardly extending portion 16 disposed so as to engage the lowermost stave to feed the same into the bending apparatus proper. To reduce the weight of the slide, it may be made in the form of an inverted dished member, of which the guide portions 15 are the inverted sides, the upwardly projecting portion 16 may be the inverted bottom, while the depending forward portion 17 constitutes the forward side of the dished member.

For reciprocating the feed slide, any suitable mechanism may be provided. I have illustrated a pair of arms 18, mounted upon a rock shaft 19. The tops of these arms are connected by links 20 with lugs 21 formed at the interior of the slide. Adjacent to the arms is mounted a shaft 22, driven from the main shaft of the machine. Upon the shaft 22 are fixed the cams 23 which are engaged by pins or projections 24, extending from the arms 18. Thus, the slide is reciprocated in accordance with the motion of the main shaft which actuates the bending apparatus and the feeding of each stave is properly timed. The cam slots 25 of the cams 23 are so shaped as to impart a quick motion to the staves to feed the same to the bending apparatus as soon as the latter is moved into proper position.

I will now describe the construction and mode of operation of the bending and forming apparatus itself.

Upon the main drive shaft 26 of the apparatus, journaled in suitable standards 27, are mounted a pair of sprocket wheels 28, over which pass the endless sprocket chains

29 to the farther end of the machine at which are mounted the standards 30, having journaled therein, the shaft 31, carrying the sprocket wheels 32. These sprockets 32 constitute the carriers for the sprocket chains at the farther end of the machine. Mounted upon pins 33, joining the adjacent links, are upstanding arms 34, carrying the forms which in the operation of the machine engage the staves to press them into the required shape. These forms are preferably constructed as follows: Carried by the upper ends of each pair of arms is a square shaft 35, upon which are fixed a number of spaced form plates 36, 37, 38, etc. These plates are formed with curved edges 39, 40 for engaging staves at the front and rear and form them with a curve corresponding to the diameter of the barrel. To form the bilge in the stave, the form plates 36, 37, 38, etc., are progressively offset from each other upon the shaft 35, so as to form the necessary curve in the direction of the length of the stave. The connection of the form plates with the square shaft may be readily effected in any suitable manner as by casting hubs 41 upon the plates and piercing the hubs by set screws 42 which clamp the latter to the shaft. Any suitable means may be used for limiting the movement of the forms with reference to the chains. In the embodiment of my invention illustrated herein, I form the pins 33 with an inwardly extending portion 43 which extend into slots 44 (Fig. 5) formed in the bottom of the outer form plates such as 36. The adjacent form plates 36 and 36^a may be provided also with interengaging noses 45, 46, the adjacent forms thus mutually supporting each other during their upward travel on the sprocket wheels 28. The noses 46 may also serve as stops to limit the movement of the stave when it is first inserted and to keep the latter in proper alignment.

45 After a stave has been fed onto the form indicated generally as A (Fig. 1) and has risen to a position about that occupied by the form plate indicated generally as X, it is actuated toward the adjacent form plate Y immediately in advance thereof to bend the stave and to clamp it in bent position. This is accomplished as follows: Mounted upon the shaft 22 are a pair of cams 47 similar to cams 23. These cams 47 are each formed with a slot 48 in which is engaged a pin 49 mounted upon a rod 50. The latter is guided by a fork 50^a straddling the shaft 22 and is connected through an adjustable connection 50^b to the lower end of a presser lever 51, which is rocked to and fro by the cam. The upper end of the lever is formed with a pivoted tip 52, held yieldingly in place by suitable means such as a spring 53. As the form plate reaches the position corresponding to X, the presser le-

ver 51 is rocked back, the tip 52 swinging behind the shaft 35 and as the lever is swung back sharply by the rapid rise of the cam, the form X is pressed toward the form Y, compressing the stave to hold it snugly between the two forms to give it the required shape. When the stave is so compressed, means are provided for locking the adjacent forms together, so as to firmly hold the stave compressed between the two forms while it travels the length of the apparatus through a drying chamber or to be otherwise treated in any suitable manner. Pivoted upon the rounded extensions of the square shafts 35 are arms 54, having hook portions 55, adapted to close over the adjacent rear shaft. Before the two forms have been pressed together, the nose 56 of the hook rides on the contiguous shaft. As soon, however, as the two forms are pressed together, the nose rides off the shaft and the hook engages the same to lock the two forms together. The chain may be given any length of travel desired and the weight thereof with the staves is supported by tracks 57 formed preferably by angle-irons supported upon suitable standards 58. Rollers 59 are mounted upon the pins 43 of the links, these rollers engaging the tracks 57 and forming an anti-friction support for the chain. When the forms reach the extreme end of the apparatus, it is necessary to disengage the hooks, so as to permit the forms to spread during their down travel over the sprocket wheels 32, and finally discharge the staves which have by that time attained their proper shape and have become set. This disengagement of the hooks is accomplished as follows: Rotating together with the sprocket wheels 32 on the sides adjacent the hooks are a pair of wheels 60, each of which is formed with inwardly extending pins or lugs 61, one of these pins being provided for each hook at a point to one side thereof. Thus, when the arm 34^a travels to the position occupied by arm 34^b, the pin 61^a reaches the position occupied by the pin 61^b, lifting the hooked arm 54 out of engagement with the adjacent shaft, uncoupling the adjacent forms and freeing the stave. The hook is kept in its released position until it falls over by its own weight and swings freely down until the forms again rise in their upward travel on the sprocket wheels 28. As soon as the stave, in the downward travel of the forms on the sprocket wheels 32, reaches a position where it can slide off the forms, it drops upon a conveyor 62, and is carried to any desired point to be stored or to be used in the building up of the barrel.

The stave bending and forming machine above described is composed of inexpensive parts, is economical in space and very efficient in operation. By reason of support-

ing the staves on edge during their travel, plenty of room is given for the warm currents of air to circulate freely between the staves, the latter presenting substantially 5 their entire surface freely to the air currents. The forms also are so constructed as to impart to the stave both the transverse and longitudinal curvature in the same operation during the travel of the conveyer.

10 It will be understood that many modifications may be resorted to within the skill of a mechanic without departing from the scope of the appended claims.

I claim:

15 1. In a stave forming machine, an endless carrier, means for supporting the staves on edge on said carrier through the major portion of the travel of the carrier, said supporting means comprising forms, and 20 means for compressing the staves in said forms.

25 2. In a stave forming machine, an endless chain, forms carried by the chain having the forming surfaces in the direction of the width of the stave disposed substantially transverse to the chain, and means for compressing the staves between the forms.

30 3. In a stave forming machine, an endless carrier, means for supporting the staves on edge on said carrier comprising forms, and means acting in the direction of motion of the carrier for compressing the staves between the forms.

35 4. In a stave forming machine, an endless carrier comprising a chain, sprockets upon which the chain is carried, forms carried by the chain, means for feeding a stave between the forms during the upward travel of the chain upon one of the sprockets, and 40 means for compressing the stave between the forms when it has reached substantially the top of the sprocket wheel.

45 5. In a stave forming machine, a pair of endless chains, forms carried thereby and having a limited movement longitudinally thereof, said forms having their forming surface directly in the width of the stave disposed substantially transverse to the chains, and means for pressing the forms 50 toward each other to compress the staves therebetween.

55 6. In a stave forming machine, a pair of endless chains, arms carried thereby capable of movement relative to the chains, forms carried by the free ends of the arms, and means for pressing the adjacent forms toward each other to compress a stave therebetween.

60 7. In a stave forming machine, a pair of endless chains, forms carried thereby, said forms comprising shafts, spaced plates mounted upon the shafts having their edges transverse to the chains curved to the required curvature of stave, said plates being 65 also progressively offset to provide for the

bilge in the stave, and means operating in the direction of motion of the chain for pressing the forms toward each other to compress a stave therebetween.

8. In a stave forming machine, a pair of 70 endless chains, upstanding arms carried thereby, a shaft mounted in each pair of arms, form plates disposed upon the shaft having a curvature in the direction of the width of the stave transverse to the chains, and means for actuating the forms to compress a stave therebetween. 75

9. In a stave forming machine, an endless chain, forms carried by the chain having the forming surfaces directly in the width 80 of the stave disposed substantially transverse to the chain, means for compressing the staves between the forms, and means for locking the adjacent forms to each other.

10. In a stave forming machine, an endless carrier comprising a chain, sprockets upon 85 which the chain is carried, forms carried by the chain, means for feeding a stave into a position between the forms during the upward travel of the chain upon one of the sprockets, means for compressing the stave between the forms when it has reached substantially the top of the sprocket wheel, and means for locking the adjacent forms to each other. 90

11. In a stave forming machine, a pair of 95 endless chains, forms carried thereby and having a limited movement longitudinally thereof, said forms having their forming surface directly in the width of the stave disposed substantially transverse to the chains, means for pressing the forms toward each other to compress the staves therebetween, and means for locking the adjacent forms to each other. 100

12. In a stave forming machine, a pair of 110 endless chains, arms carried thereby capable of movement relative to the chains, forms carried by the free ends of the arms, means for compressing the adjacent forms toward each other to compress a stave therebetween, and means for locking the adjacent forms to each other. 115

13. In a stave forming machine, a pair of 120 endless chains, arms carried thereby, shafts mounted in the arms, form plates fixed to the shafts, means for actuating the shafts toward each other to compress a stave between the opposing form plates, and means for locking the shafts to clamp the stave between the forms until it has attained its set. 125

14. In a stave forming machine, a pair of endless chains, arms carried thereby, shafts mounted in the arms, form plates fixed to the shafts, means for limiting the relative movement of the forms relative to the chains, and means for locking the shafts to clamp the stave between the forms until it has attained its set. 130

15. In a stave forming machine, a pair of

- endless chains, arms carried thereby, shafts mounted in the arms, form plates fixed to the shafts, means for actuating the shafts toward each other to compress a stave between the opposing form plates, and hooks pivoted upon each shaft to engage the adjacent shaft to lock the opposing forms to clamp the stave therebetween.
16. In a stave forming machine, a pair of endless chains, arms carried thereby, shafts mounted in the arms, form plates fixed to the shafts, means for actuating the shafts toward each other to compress a stave between the opposing form plates, and hooks pivoted upon each of the shafts having noses engaging the adjacent shaft to ride thereupon and swing free into locking position when the forms have been actuated into clamping position.
17. In a stave forming machine, an endless chain, forms carried by the chain having the forming surfaces in the direction of the width of the stave disposed substantially transverse to the chain, means for compressing the staves between the forms, means for locking the adjacent forms to each other, and means for automatically releasing the locking means.
18. In a stave forming machine, an endless carrier comprising a chain, sprockets upon which the chain is carried, forms carried by the chain, means for feeding a stave into a position between the forms during the upward travel of the chain upon one of the sprockets, means for compressing the stave between the forms when it has reached substantially the top of the sprocket wheel, means for locking the adjacent forms to each other, and means for automatically releasing the locking means.
19. In a stave forming machine, a pair of endless chains, forms carried thereby and having a limited movement longitudinally thereof, said forms having their forming surface disposed substantially transverse to the chains, means for pressing the forms toward each other to compress the staves therebetween, means for locking the adjacent forms to each other, and means for automatically releasing the locking means.
20. In a stave forming machine, a pair of endless chains, arms carried thereby capable of movement relative to the chains, forms carried by the free ends of the arms, means for pressing the adjacent forms toward each other to compress a stave therebetween, means for locking the adjacent forms to each other, and means for automatically releasing the locking means.
21. In a stave forming machine, two pairs of sprocket wheels, endless chains driven by the sprockets, forms carried thereby, means for actuating the form toward each other to compress the stave therebetween, means for locking the opposing forms to each other, and means for releasing the locking means.
22. In a stave forming machine, two pairs of sprocket wheels, chains carried thereby, forms carried by the chains, means for actuating the forms toward each other in the direction of travel of the chains, hooks for locking the forms to each other to clamp the stave therebetween, means for automatically disengaging the hooks comprising wheels rotating with the sprocket wheels at the discharge end of the chains, and projections formed upon the wheels disposed in position to raise the hooks during the course of the travel of the chains onto the said sprocket wheels.
23. In a stave forming machine, a pair of chains, shafts carried thereby, forms fixed to the shafts, means for actuating the shafts toward each other to compress a stave between the forms comprising an arm, means for reciprocating the arm, and a pivoted tip yieldably held in extended position upon the arm to freely swing under the shafts in the rearward stroke of the arm and to engage the shafts to actuate them during the forward stroke of the arm.
24. In a stave forming machine, a traveling carrier, a pair of opposed forms mounted thereon comprising spaced plates having opposed edges constituting forming surfaces curved in a direction of the width of the stave corresponding to the diameter of the barrel and disposed in a direction longitudinally of the stave corresponding to the bilge of the barrel, and means for forcing the forms together and clamping a stave therebetween during the travel of the carrier.
